AMUSEMENT PUTTING DEVICE

John F. Draper, 571 Park Ave.,
Rialto, Calif. 92376

Filed July 18, 1966, Ser. No. 3,106

Term of patent 14 years

(Cl. D34—5)

The figure is a perspective view of an amusement putting device showing my new design.

The rear unseen portion is plain. The opposite longitudinal portion is the same as that shown on the near side.

My design is characterized by a partially hollowed sphere from which leads the putting runway, all as shown.

I claim:

The ornamental design for amusement putting device, as shown and described.
